(57) **CLAIM**

The ornamental design for a touch-screen device, as shown and described.

DESCRIPTION

FIG. 1 is a front perspective view of a touch-screen device showing our new design.

FIG. 2 is a front view of the touch screen device shown in FIG. 1;

FIG. 3 is a right side view of the touch-screen device shown in FIG. 1, the left side view being a mirror image thereof; FIG. 4 is a top side view for the touch-screen device shown in FIG. 1; and,

FIG. 5 is a bottom side view of the touch-screen device shown in FIG. 1.

The broken lines shown in the drawings represent portions of the touch-screen device that form no part of the claimed design.

1 Claim, 5 Drawing Sheets
